UNITED STATES PATENT OFFICE.

LYDIA MONTGOMERY, OF COLVILLE, WASHINGTON.

SANITARY LUNCH-BOX.

1,137,160.

Specification of Letters Patent. Patented Apr. 27, 1915.

Application filed April 1, 1914. Serial No. 828,696.

To all whom it may concern:

Be it known that I, LYDIA MONTGOMERY, a citizen of the United States, residing at Colville, in the county of Stevens and State 5 of Washington, have invented a new and useful Sanitary Lunch-Box; and I do hereby declare the following to be a full, clear, and exact description of the invention, such as will enable others skilled in the art to 10 which it appertains to make and use the same.

This invention relates to an improved new and useful lunch box or receptacle.

An object of the invention is the provision 15 of a receptacle having various compartments and drawers for containing various articles of food, as well as for holding linen, knives, forks and spoons, thereby not only constituting a box for carrying ordinary 20 lunches, but providing an improved lunch pail or box of a capacity sufficient to carry enough food and utensils for a picnic or the like.

One of the features of the invention is 25 the provision of two compartments, one disposed above the other and arranged substantially centrally of the box for containing a plurality of jars, in which cream, sugar, 30 jelly, fruit, pickles and olives, and the like may be contained. These jars are provided with screw threaded connections with the bottoms of said substantially intermediate compartments, to prevent the jars from tossing about, while carrying the box.

35 In practical fields the details of construction may necessitate alterations, falling within the scope of what is claimed.

The invention comprises further features 40 and combination of parts, as hereinafter set forth, shown in the drawings and claimed.

In the drawings:—Figure 1 is a view in perspective of the improved lunch box or receptacle, showing the closure member open, in order to display the construction of 45 the interior of the box. Fig. 2 is a longitudinal sectional view on line 2—2 of Fig. 1. Fig. 3 is a vertical sectional view on line 3—3 of Fig. 1. Fig. 4 is a transverse sectional view on line 4—4 of Fig. 1. Fig. 5 50 is a sectional view on line 5—5 of Fig. 1.

Referring more especially to the drawings 1 designates a box, which may be of any suitable size or material. However, in the present instance it is shown as being rectangular in contour, and provided with a closure

2 hinged at 3, there being a suitable fastening 4 for holding the closure in a locked position. Substantially centrally of the box and arranged transversely thereof are two partition walls 5 and 6, which are spaced 60 apart, as shown to form a substantially centrally located compartment 7. The opposing faces of the partition wall 6 and the end wall 8 of the box are provided with angle members 9, forming guides to receive 65 the shelves 10, 11 and 12. The opposing faces of the partition wall 5 and the end wall 13 of the box are also provided with angle members 14 constituting guides which likewise receive shelves 15 and 16. The 70 inner face of the rear of the box is provided with angle members 17, on which said shelves 10, 11, 12, 15 and 16 also rest. Locking devices 18 are provided to hold the shelves 10, 11, 15 and 16 in place, that is, 75 against upward movement. Between the shelves 11 and 12 a drawer 19 constituting a pie tray is arranged, while between the shelf 12 and the bottom of the box a drawer 20 to contain sandwiches, cookies and the 80 like, is arranged; whereas between the shelf 16 and the bottom of the box another drawer 22 is disposed. This drawer 22 is adapted to hold chicken and fresh meats. On the shelf 15 salads and fresh fruit may be supported, while upon the shelf 16 various 85 dishes and the like may be supported. Linens may be carried upon the shelf 10, while cakes may be supported upon the shelf 11. The adjacent faces of the partitions 5 and 6 are provided with angle members 24 90 acting as guides to support the shelves 25 and 26, which are also held in place by the locking devices 27 similar to the devices 18. Below the shelf 26 and resting upon the bottom of the box is an elongated drawer 29, to hold knives, forks and spoons. The upper 95 faces of the shelves 25 and 26 are provided with disk members 30 having annular screw threaded flanges 31, in engagement with 100 which the lower closed ends (which are provided with threads 32) of the jars 33 are connected as shown. In this manner the jars are held against displacement or jolting. These jars are marked or appropriately 105 designated to contain delicatessen. The top of the box is provided with a suitable handle 34, and extending about the length of the box are heavy brace wires 35, in order to reinforce the structure.

The invention having been set forth, what is claimed as new and useful is:—

1. In combination, a lunch box provided with a compartment, a removably supported shelf slidably supported in said compartment, means for not only detachably securing said shelf supported in the compartment, but for holding the shelf in different adjusted positions, and interchangeable 10 receptacles having detachable threaded connections with said shelf.
2. In combination, a lunch box provided with a compartment, a removably supported shelf adjustably connected in said compartment,

ment, said shelf having secured thereto a plurality of members provided with interiorly threaded flanges, each flange being threaded to threads formed upon closed ends of the jar, and pivoted cam latches for holding the shelf in different adjusted positions. 20

In testimony whereof I have signed my name to this specification in the presence of two subscribing witnesses.

LYDIA MONTGOMERY.
